UNITED STATES PATENT OFFICE.

GEORGE GADKE, OF PHILADELPHIA, PENNSYLVANIA, ASSIGNOR TO WILLIAM GADKE,
OF PHILADELPHIA, PENNSYLVANIA.

IGNITION DEVICE.

Application filed February 25, 1922. Serial No. 539,066.

My invention relates to ignition circuits for internal combustion engines and more particularly relates to ignition circuits for automobiles.

5 The purpose of my invention is to provide an open and closed circuit system adapted to easy and inexpensive manufacture that will adequately and efficiently meet service requirements.

10 Thus far ignition devices are such as may be roughly divided into two types,—the open circuit and the closed circuit, each type with advantages and disadvantages with respect to the other, and it is my aim to provide improved apparatus that combines the advantages and avoids the faults of both types, the device being both open and closed.

15 In both open and closed circuit devices the ignition spark is effected by breaking a contact in the primary circuit.

20 In the open circuit type the circuit is momentarily closed and broken by cam release of a spring, contacts flying momentarily together and apart when the spring is released.

25 In this type the battery supplying the circuit does not have to supply any current whatever except during the very brief periods in which the contacts are together and consequently this type is economical with current.

30 However while economical in the use of current it is seriously faulty in its inability to synchronize properly due to its having phases, that from spring release to contact and from contact to spring breaking of contact, that do not vary proportionately with the speed of the releasing cam and therefore with the speed of the engine. The phases from synchronous spring release to contact and from contact to spring breaking of contact may for example together occupy 5° on the cam with a speed corresponding to 10 miles an hour in which event they would together occupy 10° on the cam if the speed were increased to 20 miles per hour.

35 This fault of inability to synchronize properly in the open circuit type usually outweighs its merit of economy in the use of current.

40 In the closed circuit type the battery is on circuit except when contacts are pushed mo-

mentarily apart by a cam, and this type while high in the use of current affords theoretically perfect synchronism, the separation of the contacts theoretically always taking place in phase with the cam which is turning with a velocity proportional to the speed of the engine and in phase with the engine,—nevertheless in most of these devices synchronism becomes faulty from wear of the engaging parts, a fibre rubbing block or roller being used that in service soon wears from engagement with the cam.

45 My purpose is to provide an improved ignition apparatus that is of both types, economical in the use of current by reason of the circuit being definitely open during the major portion of the cycle, and perfectly synchronous by reason of positive separation of contacts at definite positions of a cam turning in phase with the engine.

50 A further purpose is to provide an ignition system in which a revolving cam in phase with the engine presses a pivoted intermediate non-resilient member to position a contact member spring pressed toward mating engagement with a second contact member.

55 A further purpose is to so inter-relate the revolving cam, the intermediate member pressed upon it and the two contact members as to produce a succession of four-phase cycles,—a phase of positive contact breaking exactly synchronous with the cam, a phase during which the contacts are apart and the circuit open, a phase of spring return to contact and a phase during which the contacts are together and the circuit closed.

60 A further purpose is to have such spring interlocking between the functional members as will avoid danger of accidental dis- placement of any part.

65 A further purpose is to guard against accidental backfires from reverse turning of the cam by locking the cam from reverse turning.

70 A further purpose is to provide screw adjustment on one of the contact members whereby the phase of breaking contact, which is the ignition phase, may be somewhat advanced or retarded.

75 A further purpose is to provide a device having improved insulation.

Further purposes will appear in the specification and in the claims.

Figure 1 is a plan view of my device.

Figure 2 is a sectional elevation through 5 2—2 of Figure 1.

Figure 3 is a plan view of a modification, the view being similar to that of Figure 1.

Figure 4 is a detail section through 4—4 of Figure 1 to illustrate spring interlocking 10 of functional members.

Figure 5 is a detail section through 5—5 of Figure 3 to illustrate spring interlocking of functional members in the modified form 15 of Figure 3.

Figure 6 is a perspective view of another detail.

Figure 7 is a perspective view, half section, of a detail.

In all drawings the same numbers refer to 20 like parts.

Describing in illustration and not in limitation:—

On a usual timer shaft 10 I rigidly mount 25 a flange 11 recessed at 12 to drivingly interlock when turning in normal direction with lugs 13 of a sleeve 14 that carries the ignition cam 15, and to slidingly engage the lugs 13 when turning in reverse direction.

The cam is electrically insulated from the 30 sleeve 14 by means of suitable intermediate fibre 16, and the sleeve 14 carrying the cam is spring pressed to engagement with the flange 11 by a spring 17 stopped outwardly against a pin 18 through the timer shaft.

As long as the timer shaft 10 is revolving 35 in its normal direction the cam must revolve with it by reason of interlocking engagement between the lugs 13 and the flange 11, but reversal in the rotation direction of the shaft 40 does not impose a corresponding reversal in the motion of the cam because the toe of the interacting member 32 locks the cam.

The bearing 19 of the timer shaft is flanged to form a base 20 to support the make and 45 break contact mechanism.

Insulation posts 21, 22 and 23, 24 on the base carry the terminal plates 25 and 26 with screw terminals 27 and 28.

The plate 25 carries a post 29 upon which 50 is pivoted a contact-carrying member 30, a post 31 upon which is pivoted an engagement link member 32 for interaction between the cam 15 and the contact-carrying member 30, and a post 33 of reduced diameter intermediate 55 its length to give the effect of a lateral recess for interlocking stop engagement with a spring 34 rigidly attached to the contact-carrying member 30.

The plate 26 carries a post 35 upon which 60 is pivoted a contact-carrying member 36, a post 37 of reduced diameter intermediate its length to give the effect of a lateral recess for interlocking stop engagement with a spring 38 rigidly attached to the contact-carrying member 36, and a threaded split

bearing 39 for tightly and adjustably positioning a set screw stop 40.

The contact-carrying members 30 and 36 carry respectively contacts 41 and 42 adapted to mating engagement. Of these the contact 70 42 on member 36 non-resiliently engages the contact 41 on member 30 which is stiff and spring pressed by means of the spring 34 toward mating engagement with the contact 42.

The body portions 43 and 44 respectively of the pivoted contact-carrying members 30 and 36 are approximately non-resilient under such stresses as they may be subjected to from the springs 34 and 38, and mating contact 80 between the members 41 and 42 is unaccompanied by any resilient departure of the pivoted member 36 from stop engagement with the screw stop 40, the spring 38 pressing the member 36 upon the screw stop being sufficiently strong to insure this non-resilience of position with existing stresses.

Ignition is effected by positive non-resilient interaction of parts between the cam and contact 41, avoidance of resilience of parts between the cam and the contact positioned by the cam being requisite for maintenance of perfect synchronism between them, any spring in these intermediate parts introducing a lag between the motion of the contact and the position of the cam, a lag which would not vary proportionately with the speed of the cam, and in fact which would not vary at all, being the same at all speeds.

The pivoted contact-carrying member 30 90 is spring pressed by the spring 34 toward mating engagement of the contacts 41 and 42 and is stopped either upon the contact 42 or upon the pivoted link 32 according to the position of this link as determined by the 95 phase of the cam 15; when stopped by the pivoted link the contacts are open.

The cam 15 by interaction with the pivoted link 32 and the spring pressed contact-carrying member 30 is designed to produce a continuous series of four-phase cycles of which the ignition phase, that is the phase of breaking contact between the members 41 and 42, is exactly synchronous with the cam and therefore exactly synchronous with the engine synchronously driving the cam.

Each cycle in this continuous series of four-phase cycles has a phase in which the cam positively and non-resiliently moves the contact 41 from touching engagement with the contact 42 (this is the ignition phase and it is exactly synchronous with the cam), a phase during which the cam maintains separation between the contacts, a phase of cam release and spring return of the member 41 to contact with the member 42 from the action of the spring 34, and a phase of mating contact between the members 41 and 42.

The pivoted link member 32 serves not only to interact between the cam and the contact-

carrying member 30 but also locks the cam from turning in reverse direction, irrespective of any reversal in the turning direction of the timer shaft.

8 The screw stop 40 in Figure 1 positions the contact stop 42 and thereby provides means for easy slight adjustment in the time of ignition. The main purpose of this stop is to take the wear of contacts 41 and 42. It is 10 also used for initial adjustment. Variation in different motors also makes it desirable to have an adjustment here to accommodate individual motors or the whim or purpose of the user.

15 The functional members interlock with one another so that they may not be accidentally displaced.

In Figure 1 the spring 34 carried by the member 30 interlocks with the recessed post 20 38 the outer end of the spring latching within the recess thus maintaining the member 30 in its proper position and yet providing means for its very easy removal.

The contact-carrying member 30 and the 25 pivoted link member 32 interlock, by reason of extensions 46, on the member 30.

The contact-carrying member 36 is maintained in its proper position by interlocking of the spring 38 with the recessed post 37, 30 the end of the spring latching in the recess, and the point of the adjusting screw fits into the depression or opening 36' in this member, assisting also in the maintenance of the position of member 36.

35 In Figure 3 the contact-carrying member 30' and the pivoted link 32' interlock by projections 46' on the contact-carrying member 30' and the spring 34' carried by the member 30' locks in a recess of the post 33'; and the member 36' is maintained in its position by the spring 38' locking in a recess of the post 37'.

The pivoted link member 32 performs the double function of interacting between the 45 cam and the contact-carrying member 30 and of locking the cam against reverse turning.

The cam contour engaging the toe 47 of the pivoted link 32 comprises alternate inner and outer portions of the perimeter of a wheel, so that the cam in effect is a wheel having a succession of transverse recesses around its periphery.

The passage from an outer to an inner portion is abrupt to secure locking engagement 55 with the toe 47 from reversal of the wheel, and the passage from an inner to an outer portion of the periphery is abrupt to secure abrupt action between the cam and toe for sharp and positive movement of the contact 60 41 from stop engagement with the contact 42.

There is no necessity for perfect synchronization in the return of the contact-carrying member 30 to stop engagement with the contact-carrying member 36 and in view of the 65 fact that the return is a spring return, theo-

retically it will not be absolutely synchronous with the cam, the lag of the spring not varying proportionately with the speed of the cam.

A novel feature of my invention is the improved means for simultaneously insulating and positioning the terminal plates 25 and 26 with respect to the base 20. I provide hard medially flanged sleeve insulation posts 21, as best seen in the half section perspective view of Figure 7. In practice these posts are conveniently made of bakelite or other similar hard insulation material, and are made to exact size. The lower portion 50 of the post forms a hard dowel to exactly fit a counterbore 51 of the base 20; the flange portion 52 is the insulation support between the terminal plate and the base; the upper portion 53 is a hard dowel exactly fitting the corresponding hole through the terminal plate. The dowel portions 50 definitely position the posts upon the base; the flange portions 52 simultaneously insulate and support the plate from the terminal, and the dowel portions 53 definitely position the plate with respect to the insulation members and therefore with respect to the base. After the plate is in place the posts are capped with insulating washers 54, then with metal washers 55, and screws 56 through the washers and posts into the base rigidly fasten base, insulation posts and plate together.

In normal operation the ignition device is used in conjunction with the usual distributor preferably operated by the timer shaft. As the operation of this distributor is well known and does not directly bear upon my invention I have not shown it in the drawings.

I have electrically insulated the cam and the link and the contact members from the shaft bearing, but am well aware that my invention could be modified by insulating the contact 41 from the functional members 30, 32 and 15 in which event it would not be necessary to insulate these functional members.

In operation my open and closed circuit device, with the usual battery and distributor, is in the primary circuit of an internal combustion engine, the cam 15, the timer shaft 10, and the engine being relatively adjusted to be relatively in phase with one another.

The cam turning in phase with the engine successively strikes the toe of the pivoted link swinging the link to swing the contact member 30 from stop engagement with the contact 42 to give the ignition spark, rides the toe of the link upon its outer portion to lock the contact member 30 from return to stop engagement with the contact 42, and then releases the lock permitting the spring return of the contact member 30 to stop engagement with the contact 42, after which the cycle is repeated.

In view of my invention modifications and

variations will without a doubt become evident to others skilled in the art, to meet individual whim or particular need, and I claim all such modifications and variations 5 in so far as they fall within the reasonable spirit and scope of my invention.

Having thus described my invention what I claim as new and desire to secure by Letters Patent is:—

- 10 1. In an ignition device, a timer shaft, a cam mounted thereon and insulated therefrom, means for driving the cam by the timer shaft, a bearing for the timer shaft, terminal plates on the bearing insulated therefrom, stiff contact members on the terminal plates spring pressed into contact engagement and a pivoted stiff member on one terminal plate simultaneously engaging the cam and one contact member to sequentially separate the 20 contact members from engagement.
- 15 2. In an ignition device, a timer shaft, a cam mounted thereon and insulated therefrom, means for driving the cam by the timer shaft, a bearing for the timer shaft, terminal plates on the bearing insulated therefrom, stiff contact members on the terminal plates spring pressing into contact engagement, an 25 adjustable stop for the position of one of these contact members and a pivoted stiff member on one terminal plate engaging the cam on one side and the other contact member 30 on the other to separate the contact members from engagement.
- 30 3. In an ignition device, a timer shaft, a cam mounted thereon driven thereby and electrically insulated therefrom, a terminal plate, a stiff contact member pivotally mounted on the terminal plate, a recessed post on the terminal plate, a spring on the contact member interlocking with the recess of the 40 post to prevent movement along the length of the post and pressing against the post, a stiff pivoted link mounted on the terminal plate to simultaneously engage the cam and 45 the contact member, interlocking portions on the contact member and the link, a second terminal plate and a stiff contact stop for the contact member mounted on the second terminal plate.
- 45 5. In an ignition device, a timer shaft, a flange thereon, a cam mounted on the shaft engaging the flange, a spring on the shaft pressing the cam to engage the flange, and interlocking between the flange and cam interrelating them so that the flange is adapted 55 to drivingly engage the cam when turned in normal direction and slidingly engage the cam when the shaft is turned in reverse direction, a stiff pivoted contact member, a stiff 60 contact stop adapted to abrupt stop engagement with the pivoted contact, a spring pressing the pivoted contact member into mating engagement with the stop contact and a stiff movable member engaging the pivoted contact 65 member and at the same time slidingly

engaging the cam with normal direction of rotation of the cam and locking the cam from reverse turning.

5. In an ignition device, a timer shaft, a flange thereon, a cam mounted on the shaft 70 engaging the flange, a spring on the shaft pressing the cam to engage with the flange, interlocking portions on the flange and cam interrelating them so that the flange is adapted 75 to drivingly engage the cam when turned in normal direction and slidingly engage the cam when turned in reverse direction, a stiff pivoted contact member, a stiff contact stop adapted to abrupt stop engagement with the pivoted contact, a spring pressing the pivoted contact member into mating engagement 80 with the stop contact, a stiff pivoted intermediate member simultaneously engaging the pivoted contact member and the cam locking the cam from reverse turning with reverse 85 turning of the shaft and with normal turning of the shaft and cam periodically positively moving the pivoted contact member from mating engagement with the contact stop.

6. In an ignition device, a timer shaft, a bearing therefor, a flange base on the bearing, a cam mounted on the shaft and insulated therefrom, terminal plates on the base and insulated therefrom, a stiff contact member pivoted on one plate, a stiff contact stop 90 on the other plate adapted to abrupt stop engagement with the pivoted contact member, a stiff pivoted intermediate member on the first plate simultaneously engaging the pivoted 95 contact member and the cam and with normal direction of turning of the cam periodically moving the pivoted contact member from mating engagement with the contact stop and locking the cam from reverse turning, and a spring on the first plate pressing 100 the pivoted contact member into mating engagement with the stop contact.

7. In an ignition device, a timer shaft, a bearing therefor, a flange base on the bearing, a cam mounted on the shaft and insulated therefrom, terminal plates on the base and insulated therefrom, a stiff contact member pivoted on one plate, a stiff contact stop 110 on the other plate adapted to abrupt stop engagement with the pivoted contact member, a stiff member between the pivoted contact and the cam locking the cam from reverse turning and periodically positively moving the pivoted contact member from mating engagement with the stop contact, 115 and retractive means for returning the pivoted member to mating engagement with the stop contact.

8. In an ignition device, a timer shaft, a bearing therefor, a flange base on the bearing, a cam mounted on the shaft and insulated therefrom, terminal plates on the base and insulated therefrom, a stiff contact member pivoted on one plate, a stiff stop contact member on the other plate adapted to abrupt 120

130

stop engagement with the pivoted contact member, a stiff member between the pivoted contact member and the cam locking the cam from reverse turning and periodically posi-

5 tively moving the pivoted contact member from mating engagement with the stop contact, an adjustment screw mounted upon the second terminal plate for slight adjustment of the position of the stop contact and re-
10 tractive means for returning the pivoted contact member to mating engagement with the stop contact, the stop contact being mounted on a member pivoted on the second plate resiliently pressed into engagement against

15 the end of the adjustment screw.

9. In an ignition device, a timer shaft, a bearing therefor, a flange base on the bearing, a cam mounted on the shaft and insulated therefrom, terminal plates on the base and insulated therefrom, a stiff contact member pivoted on one plate, a stiff stop contact member pivoted on the other plate adapted to abrupt stop engagement with the first pivoted contact member, a stiff member between the first pivoted contact and the cam locking the cam from reverse turning and periodically positively moving the pivoted contact member from mating engagement with the stop contact, a spring on the stop contact member, posts on the second plate, the first for stop engagement with the stop contact member and the second for stop engagement with the spring, an interlocking between the spring and second post to prevent accidental displacement, and retractive means for returning the first pivoted contact member to mating engagement with the stop contact.

10. In an ignition device, a timer shaft, a bearing therefor, a flange base on the bearing, a cam mounted on the shaft and insulated therefrom, terminal plates on the base and insulated therefrom, a stiff contact mem-

ber pivoted on one plate, a stiff contact stop on the other plate adapted to abrupt stop engagement with the pivoted contact member, a stiff intermediate member between the pivoted contact member and the cam periodically positively moving the pivoted contact member from mating engagement with the stop contact, a spring on the pivoted contact member, a recessed post on the first plate stopping and interlocking with the spring, the spring pressing the contact member into stop engagement with the contact stop, and an interlocking between the intermediate member and the pivoted contact member.

11. In an ignition device, a timer shaft, a bearing therefor, a flange base on the bearing, a cam mounted on the shaft and insulated therefrom, terminal plates on the base and insulated therefrom, a movable stiff contact member on one plate, a mating stiff stop contact therefor on the other plate, a recessed post on the first plate, a spring on the first contact member stopping against and latching within the recess of the post, a recessed post on the second plate, a spring on the stop contact member stopping against and latching within the recess of the post on the second plate, and means interlocking with the first contact member slidingly engaging the cam.

12. In an ignition device, a timer shaft, a cam mounted thereon, a stiff movable contact member, a stiff stop contact member to mate therewith, stiff operating means between the cam and movable contact member latching with said member to prevent displacement of the operating means, a post, a spring on the movable contact member with an outer end pressing against and latching with the post, another post and a spring on the stop contact member having an outer end pressing against and latching with the other post.

GEORGE GADKE.
